(57) **CLAIM**

The ornamental design for a dental guard and tray, as shown and described.

DESCRIPTION

FIG. 1 is an upper front exploded perspective view of a dental guard and tray of our new design.

FIG. 2 is a frontal view of the dental guard and tray of FIG. 1.

FIG. 3 is a rear view of the dental guard and tray of FIG. 1. FIG. 4 is a bottom plan view of the dental guard and tray of FIG. 1.

FIG. 5 is a top plan view of the dental guard and tray of FIG. 1.

FIG. 6 is a right side view of the dental guard and tray of FIG. 1.

FIG. 7 is a left side view of the dental guard and tray of FIG. 1.

FIG. 8 is an upper front assembled perspective view of a dental guard and tray of our new design; and, FIG. 9 is a perspective view of the dental guard.
